CLAIM

The ornamental design for the grate lid for swim spas as shown and described.

DESCRIPTION

FIG. 1 is a front perspective view of the grate lid for swim spas showing our new design.

FIG. 2 is a front side view of the grate lid for swim spas.

FIG. 3 is a rear side view of the grate lid for swim spas.

FIG. 4 is a left side view of the grate lid for swim spas.

FIG. 5 is a right side view of the grate lid for swim spas.

FIG. 6 is a top view of the grate lid for swim spas.

FIG. 7 is a bottom view of the grate lid for swim spas.

FIG. 8 is a front perspective view of the grate lid for swim spas showing our new design according to a second embodiment.

FIG. 9 is a front side view of the grate lid for swim spas according to the second embodiment.

FIG. 10 is a rear side view of the grate lid for swim spas according to the second embodiment.

FIG. 11 is a right side view of the grate lid for swim spas according to the second embodiment.

FIG. 12 is a left side view of the grate lid for swim spas according to the second embodiment.

FIG. 13 is a top view of the grate lid for swim spas according to the second embodiment; and,

FIG. 14 is a bottom view of the grate lid for swim spas according to the second embodiment.

The broken line areas as showing portions of the grate lid for swim spas form no part of the claimed design.
